UNITED STATES PATENT OFFICE.

JOHN C. REUTER, OF ST. LOUIS, MISSOURI.

DESIGN FOR AN AUTOMOBILE-BODY.

SPECIFICATION forming part of Design No. 36,040, dated September 2, 1902.

Application filed July 3, 1902. Serial No. 114,322. Term of patent 3½ years.

To all whom it may concern:

Be it known that I, JOHN C. REUTER, a citizen of the United States, residing at St. Louis, in the State of Missouri, have invented and produced a new, original, and ornamental Design for an Automobile-Body, of which the following is a specification.

The invention relates to a new, original, and ornamental design for an automobile-body, and it has for its object to provide an ornamental design of that character.

The leading feature of the design resides in the design forming the subject-matter of the accompanying illustration.

15 The figure of the drawing is a perspective view of an automobile-body, showing my new and original design.

Referring to the drawing, 1 designates the body of an automobile, having a tapering 20 projecting front portion and presenting the appearance of the prow or bow of an iron-clad vessel. The body is also provided above the tapering projecting portion 2 with an

eagle's head 3, having an open beak containing the headlight 4. The rear portion of the 25 body is rounded at the base and is provided with a projecting upper portion 5, approximately oblong in plan view and having a rounded front end 6, and the rear face 7 is provided with a curved lower portion located 30 above the rounded rear end portion 8. The body is also provided at the front portion with approximately semicircular recesses 9, having angularly-disposed faces 10 at the back.

35

What I claim is—

The ornamental design for an automobile-body, as herein shown and described.

In testimony that I claim the foregoing as my own I have hereto affixed my signature 40 in the presence of two witnesses.

JOHN C. REUTER.
